Primary Examiner — Susan Bennett Hattan*Assistant Examiner* — Janice Hallmark(74) *Attorney, Agent, or Firm* — Andrew S. Langsam; Pryor Cashman LLP(57) **CLAIM**

The ornamental design for vaporization apparatus, as shown and described.

DESCRIPTION

FIG. 1 is a front elevational view of the vaporization apparatus, showing my new design;

FIG. 2 is a rear elevational view thereof;

FIG. 3 is a right side view thereof;

FIG. 4 is a left side view thereof;

FIG. 5 is a top plan view thereof; and,

FIG. 6 is a bottom view.

The broken lines in the drawings depict parts of the vaporization apparatus that form no part of the claimed design.
